UNITED STATES PATENT OFFICE.

JOHN H. MILLER, OF RISING SUN, OHIO.

HOISTING APPARATUS.

SPECIFICATION forming part of Letters Patent No. 285,915, dated October 2, 1882.

Application filed August 6, 1883. (No model.)

To all whom it may concern:

Be it known that I, JOHN H. MILLER, a citizen of the United States, residing at Rising Sun, in the county of Wood and State of Ohio, 5 have invented a new and useful Hoisting Apparatus, of which the following is a specification, reference being had to the accompanying drawings.

This invention relates to hoisting-machines, 10 and more especially to that class of hoisting apparatus which is employed for raising the bents of barns and other buildings in course of construction; and it has for its objects to produce a machine which shall possess superior 15 advantages in point of simplicity, cheapness, ease of operation, and general efficiency.

To this end it consists in certain improvements in the construction of the same, which 20 will be hereinafter fully described, and particularly pointed out in the claims.

In the drawings hereto annexed, Figure 1 is a perspective view of my improved hoisting apparatus. Fig. 2 is a vertical longitudinal 25 sectional view of the same. Fig. 3 is a vertical transverse sectional view taken through the front standard. Fig. 4 is a front view. Fig. 5 is a sectional view on the line $x-x$ in Fig. 2, and Fig. 6 is a detail view.

The same letters refer to the same parts in 30 all the figures.

A in the drawings designates the front standard, which comprises a pair of sides or legs, B B, connected at their upper ends by means of transverse bolts C, passing through a spacing-block, D, which is provided with a series 35 of vertical slots, E, in which pulleys F F are journaled, as shown. The legs B B are connected near their lower ends by means of a tightening-bolt, G, turning freely in one of said 40 legs, and working in a nut, H, which is countersunk in the other. Above the said bolt is arranged a transverse rod, I, upon which is coiled a spring, J, the action of which is to force the said legs apart from each other. The 45 front sides of the legs B are provided near their lower ends with a pair of turn-buttons, K, serving to retain in position a detachable slotted strip, L, the function of which is to 50 guide the posts of the bents into place. The legs B are provided upon their rear sides, near their upper ends, with perforated lugs or eyes

M, to receive a transverse hinge-rod, N, upon which are hinged a pair of braces, O O, which are connected at various points by rungs or cross-braces P P, so as to form a ladder by 55 which the top of the hoisting-machine may be reached. The inner sides of the braces O are provided, at the lower ends of the latter, with plates Q, having inturned points or prongs R. Passing through the plates near their lower 60 ends is a tightening-bolt, R, turning freely in one of the braces, and working in a nut, S, countersunk in the other. Above the said tightening-bolt is arranged a transverse rod, T, upon which is coiled a spring, U, serving 65 to force the said braces apart. The lowermost connecting-rings P are provided with slots V, working on the fastening-pins W, so as to give sufficient spring or elasticity to the lower ends of the braces O.

X is the hoisting-rope, which is reeved over the pulleys F and over the pulleys Y in a block, Z, to which one end of the said hoisting-rope is attached. The other end of the rope X passes from one of the pulleys F over the pulley in 75 a loose block, A², which is temporarily arranged in any position suitable for the application of the draft.

The operation of my invention will be readily understood from the foregoing description, 80 taken in connection with the drawings hereto annexed. For manipulating a bent, two of the machines are required, which are arranged at the corners of the building, they being clamped upon the sills facing the bent which 85 is to be raised. The points or prongs R prevent any possibility of displacement. The pulley-block Z of each machine is made fast to the bent, draft is applied to the other end of the rope, and the bent is thus easily raised. 90 Hooks or stays B² serve, during operation, to brace the legs B and braces O. When the machine is not in use, these stays may be unhooked and the device folded for storage or transportation.

I claim as my invention and desire to secure by Letters Patent of the United States—

1. In a hoisting-machine for raising bents, the front standard consisting of a pair of legs connected at the top by bolts passing through 100 a spacing-block having a series of slots in which pulleys are journaled, in combination

with braces hinged near the upper ends of said legs, and means for clamping said legs and braces upon a sill, substantially as set forth.

5. 2. The front frame or standard comprising a pair of legs connected near their upper ends by means of a spacing-block in which a series of pulleys is journaled, in combination with a tightening-bolt arranged transversely in the lower ends of said legs, turning freely in one of the latter and working in a nut countersunk in the other, and a transverse brace having a coiled spring which serves to force the said legs apart, substantially as set forth.

15 3. The combination, with the front standard, the legs of which are provided near their lower ends with turn-buttons, as set forth, of a slotted guide-piece secured detachably to said standard by means of said turn-buttons, as set forth.

4. The combination, with the front standard, constructed substantially as set forth, and provided on its rear side, near its upper end, with eyes or perforated lugs having a transverse hinge-rod, of the braces hinged upon said rod, 25 rungs or cross-braces connecting the said braces, plates secured to the lower ends of said braces, and having inturned points or prongs, a transverse tightening-bolt, and a 30 transverse rod having a coiled spring serving to force the lower ends of said braces apart, substantially as set forth.

5. The combination, with the hinged braces having their lower ends connected by a tightening-bolt, of transverse rungs or cross-braces connecting the said braces, the lowermost of said rungs being provided with slots working loosely upon their fastening-pins, whereby sufficient spring is given to the lower ends of the braces, as set forth.

6. The herein-described hoisting device, comprising, essentially, the front standard consisting of legs connected at their upper ends by a spacing-block having a series of pulleys, braces hinged to the upper rear side of said standard, tightening-bolts connecting, respectively, the lower ends of the legs and braces, springs arranged to force the lower ends of said legs and braces apart, a block having several pulleys, a hoisting-rope attached to the 45 said block and reeved over its pulleys and over the pulleys at the upper end of the front standard, and a single guide-pulley adapted to be secured detachably in any desired position convenient to the draft or power, substantially as set forth.

In testimony that I claim the foregoing as my own I have hereto affixed my signature in presence of two witnesses.

JOHN H. MILLER.
